(57) CLAIM

The ornamental design for a lounge chair, substantially as shown and described.

DESCRIPTION

FIG. 1 is a perspective view of a lounge chair showing our new design;

FIG. 2 is a right side elevational view thereof;

FIG. 3 is a close-up of a section of the chair, from a right side elevational view;

FIG. 4 is a left side elevational view thereof;

FIG. 5 is a rear elevational view thereof;

FIG. 6 is a perspective view thereof;

FIG. 7 is a close-up of a section of the chair, from a perspective view thereof, from the upper left side and back;

The wicker surface weaving and edge braiding shown in FIG. 3 is representative of the weave and braiding throughout the chair. The weave and braiding are depicted in fragmented portions on the remainder of the drawings for convenience and to avoid crowding of the drawing, which fragmented portions are understood to be representative of the weave and braiding as shown in FIG. 7, which repeats uniformly throughout the circumscribed areas of FIGS. 1 through 7.

FIG. 8 is a perspective view of a second embodiment of the chair of FIG. 1, in which the surface treatment of the chair is not depicted.

FIG. 9 is a right side elevational view of the chair, which is a second embodiment of the chair of FIG. 1, in which the surface treatment of the chair is not depicted.

FIG. 10 is a left side elevational view of the chair, which is a second embodiment of the chair of FIG. 1, in which the surface treatment of the chair is not depicted.

FIG. 11 is a rear elevational view of the chair, which is a second embodiment of the chair of FIG. 1, in which the surface treatment of the chair is not depicted; and,

FIG. 12 is a perspective view of the chair, which is a second embodiment of the chair of FIG. 1, in which the surface treatment of the chair is not depicted.
